BUCKLE AND STRAP FOR COTTON BALES

Albert P. J. Voigt, John Donald Morhan, and
Francis Jean Herbellin, Galveston, Tex.

Application January 2, 1932, Serial No. 584,514

6 Claims. (Cl. 24—22)

The invention relates to an improvement in bale ties or buckles and straps particularly of the type used in baling cotton.

It is one of the objects of the invention to provide an improved tie wherein projections are formed upon the tie so that they will engage the buckle to prevent slipping of the tie.

Another object of the invention is to provide a bale tie adapted to be folded back beneath itself and having projections thereon to engage with each other to prevent slipping of the tie.

Another object of the invention is to provide a bale tie having projections or lugs formed thereon which are spaced apart at least a distance equal to the length of the portion of the band which is to be curved around the buckle so that the buckle is positioned between two adjacent lugs.

Another object of the invention is to provide a bale tie having substantially semi-circular depressions formed therein so that the lug formed by such depression will extend from the opposite side of the tie to engage the buckle and prevent slipping of the tie when placed under tension.

Another object of the invention is to provide an improved buckle which will not release the bale tie when the buckle is subjected to excessive stresses.

Still another object of the invention is to provide a bale tie having projections thereon wherein one of the faces of the projection is inclined at a steep angle with respect to the surface of the tie so that a shoulder is formed which will engage the buckle to prevent slipping of the tie.

Other and further objects of the invention will be readily apparent when the following description is considered in connection with the accompanying drawing wherein:

Fig. 1 is a top plan view of the improved bale tie and buckle with the parts in position as they would be when the tie is engaged about a bale.

Fig. 2 is a broken sectional view along the center line of the tie and buckle shown in Fig. 1 and illustrating the tie in position with the baled material pressing against the end of the tie to hold it in position.

Fig. 3 is an elevation of a bale which is tied with straps and buckles embodying the invention.

In connection with the baling of cotton and similar materials where the bale is formed under enormous pressure it is imperative that the bale ties or straps serve to securely confine the material. Various types of bale ties have been provided but in a majority of these experience has taught that the strap will slide or give when the bale is subjected to undue stress or shocks such

as encountered in loading or unloading the bales or when being compressed in storage. Various types of buckles have been devised to hold the ends of the ties in proper position but it has been found that in order to obtain a positive grip of the tie upon the buckle that projections or lugs should preferably be formed in the strap or tie so that these lugs will engage the buckle and prevent slipping of the tie after the bale has been formed.

With this in mind, the present invention has been devised and in Fig. 3 a bale is indicated generally at 2. It is customary to confine this bale with a plurality of straps or ties such as 3. In forming the bale the material is compressed and these ties 3 are passed around the material. A buckle such as 4 is carried by one end of the bale tie and the opposite end of the tie is passed through this buckle and recurved or folded beneath itself and the material is then released by the press so that it will expand to engage the folded end and retain it against slipping or removal.

Fig. 1 shows an enlarged view of the tie 3 and the buckle 4 but the parts thereof are best seen in section in Fig. 2. The tie or strap 3 has one end 6 thereof passed about the side member 7 of the buckle 4. The buckles 4 are usually attached to one end of the strap 3 by a machine operation and are provided for the compress in this condition. It should be noted that the end 6 is passed about the side member 7 and is crimped or bent sharply at 8 and 9 so that the side member 7 is crimped in between the surfaces of the tie. When the tie is crimped as at 8 and 9 there will be no slipping and it will securely retain its hold upon the buckle. However, the opposite end of the tie indicated at 10 cannot be crimped by a machine operation as the point, such as 11, thereof, which is to be curved about the side member 12 of the buckle 4, cannot be determined until the bale has been formed.

It is usual to have these ties or straps 3 passed manually about the bale and to have the end 10 passed through the opening 13 of the buckle and bent beneath the flat portion 14 of the tie or, as an alternative and as the most common method the tie man estimates the size of a bale by passing the straps around the bale and then bending the end 10 of the strap 3 as at 11 so that he has then determined the size of the bale. After the end 10 has been bent beneath the portion 14, but sometimes slightly away therefrom, the curved portion or loop 15 thus formed is passed over the projecting end 16 of the buckle 4 by holding the

portion 14 at substantially a right angle to the plane of the buckle so that it will pass over the projecting end 16 and through the space 17 formed between the end 16 of the buckle and the 5 downwardly turned end 18 which serves as a safety catch or latch for the buckle. In this manner it will be readily apparent that the tie may be quickly formed and slipped onto the buckle by the tie man without the aid of any mechanical means.

It will be particularly noted that when the tie or strap is bent in this manner that it cannot be crimped or bent sharply due to the stiffness of the material of which the tie is made. Where the 15 bend or curve of the material around the side of the buckle is not sharp the tie will be pulled from the buckle by the stress caused by the material when it expands.

The present invention in part relates to a manner and mechanism which will prevent slip- 20 page of this manually placed end of the strap which includes a plurality of lugs or projections 20 which are formed in the tie or strap by making depressions 21 in the surface thereof. These de- 25 pressions are of a particular configuration, which is best seen in Fig. 1, in order to provide a properly shaped projection or lug to engage the side member 12 of the buckle.

These depressions 21 are formed with a die or 30 stamp which has a crescent shaped face 23 with a crown 24 extending from the concave side thereof. In this manner the face 22 is formed with a considerable amount of material depressed by the crown 24 to back up or reinforce the shoulder 22.

As seen in Fig. 1, these depressions 21 are of 40 substantially semi-circular formation but are made with the stamping surface of the tool at an inclination to the plane of the tie so that a steep face or shoulder 22 is formed as a projection from the opposite side of the strap. This shoulder 22 is arranged to abut against the side member 12 of the buckle as best seen in Fig. 2. When the shoulder or steep surface so abuts against the buckle no amount of pulling upon the band due to 45 the expansion of the material will cause the tie to slip around the buckle. This has been found to be due first to the fact that the shoulder 22 firmly contacts against the side member 12 of the buckle and in order to have any slippage it would 50 be necessary for the projection 20 to be ironed out by the buckle. The material of the strap is too rigid to permit this because of the particular formation of the depression 21 so that the shoulder 22 is backed up by the material in the crown 24 to 55 form a sturdy shoulder and the strap is thus properly retained about the buckle.

In some instances, however, due to excessive shock, the projection 20 may be depressed and 60 permit a slight movement or slippage of the tie. When this occurs, however, the projection 25 will move to the left as viewed in Fig. 2, whereas the projection 26 will move to the right as viewed in Fig. 2. It is therefore apparent that these two 65 projections will engage each other and limit any slipping movement. If, however, these projections 25 and 26 should also pass each other the projection 25 then abuts against the buckle 12 and serves to stop any slipping movement. It 70 is to be understood that there are a considerable number of these lugs 20 as seen in Fig. 2. All of these lugs are uniformly spaced so that at the time the lug 25 engages 26 there will be a considerable number of such contacts and it has 75 been found in practice that the ties do not slip.

When the end 10 is folded back beneath the portion 14 and the pressure released from the bale the baled material 30 expands to engage the face 31 of the end 10 and causes the end 10 to be moved up against the portion 14 of the tie as seen in Fig. 2. There will be a certain amount of frictional engagement between the material 30 and the surface of the tie. It has been found, however, that this frictional contact is not of material advantage but that the advantage is obtained by pressing the end 10 against the outer portion 14 of the tie and when lugs such as are provided in this construction are present these lugs will engage each other or the buckle and the pressure against the surface 31 is so great that the lug 25 cannot move over the lug 26 nor can the surface 22, engaging the side member 12 of the buckle, move away from the buckle a sufficient distance to allow the strap to slip around the buckle.

The buckle 4 is of special construction in that the end 16 is a direct continuation of the side member 12. The end portion 35 of the buckle is continued beyond the side member 12 of the buckle and is turned downwardly as at 18 so that it passes below the plane of the side member 12 and the end 16. This is known as a safety buckle because any stresses on the tie member 3 are resisted by the hooked end 18 passing about the side member 12. Thus the side member 12 is supported by the hook 18 and by the opposite end 36 so that it is in the form of a pin supported at both ends as distinguished from the usual C type of buckle which merely relies upon the stiffness of the buckle material to retain the buckle 35 in proper form.

What is claimed as new is:

1. A bale tie and a buckle having a rectangular loop, said tie being extended through said loop and folded back under itself, a plurality of lugs 40 formed in one end of said tie, each of said lugs having one steep face, said steep face being positioned to engage the buckle on the outer end face thereof when the tie is recurved around the buckle.

2. A bale tie of the character described including a band and a buckle, one end of said band being fixed to said buckle, the other end of said band being passed through said buckle and curved back beneath itself, and lugs formed in the last named 50 end of the band projecting inwardly toward the bale before passing through said buckle and positioned to abut against the outer side of the buckle when the band is placed under tension.

3. In combination, a buckle, a bale tie passing 55 through the buckle, folded back, and curved beneath itself so that the baled material will press the portion which is folded back, in a direction outwardly against the uncurved portion, and a plurality of projections formed in said tie so that 60 those on the curved portion will engage the projections on the uncurved portion to prevent slipping of the tie.

4. In combination, a buckle, a bale tie, a plurality of uniformly spaced lugs projecting from 65 the side of said tie presented toward said bale, a steep face on one side of each lug, the outer side thereof having a gradual slope, said steep faces being so arranged that when said tie is passed through a buckle and folded back the same 70 will engage the tie buckle or each other when the tie is in position on the bale.

5. In combination, a bale tie buckle, a cotton bale tie including a band of metal, and a plurality of spaced substantially semi-circular de- 75

- pressions formed on the outer side thereof intermediate the edges of said band whereby lugs are caused to project inwardly from said band, forming shoulders thereon, so that when the free end 5 of said band is passed through said bale tie buckle and recurved said lugs on the recurved end present said shoulders toward said buckle and engage the outer end of said bale tie buckle to fix the tie in adjusted position.
- 10 6. In combination, a buckle, a bale tie wherein one end is passed through the bale tie buckle and folded back beneath itself, a plurality of pro-

jections on the tie, said projections being sharply inclined in one direction whereby steep faces are formed on one side thereof, said steep faces being presented away from the buckle when said tie is extended around the bale and brought up toward the buckle, so that they will engage each other on adjacent faces near the end of the tie when the end of the tie is extended through said buckle and folded back away from said buckle.
